H. Goehtz,
By Markel Clark
Atty.*

UNITED STATES PATENT OFFICE.

HERMANN GOEHTZ, OF BERLIN-SCHONEBERG, GERMANY.

GAS PRODUCER.

Application filed April 20, 1922. Serial No. 555,771.

To all whom it may concern:

Be it known that I, HERMANN GOEHTZ, a citizen of the German Realm, residing at Berlin-Schoneberg, Germany, have invented certain new and useful Improvements in Gas Producers, of which the following is a specification.

This invention has for its object to provide an improved gas producer of the under-
10 feed type in which the fuel is supplied continuously by mechanical means.

Compared with the known apparatus of this type, the improved gas producer works in the reverse direction. The blast is led to
15 the surface of the fuel that has been reduced to ashes, and the ashes are simultaneously removed from the gas producer at that point.

A constructional form of the improved
20 gas producer according to this invention is illustrated by way of example in the accompanying drawing in vertical section.

Referring to the drawing, the producer shaft 1, the cross-sectional area of which in-
25 creases towards the top, has an upper part 2 of refractory brickwork, its lower part 3, which is provided with outlet openings 31 for the gas, being iron. A fuel-feed pipe 4 having a mouthpiece 5 is connected up to
30 the lower part 3 of the shaft so as to form a continuation thereof.

Around the lower part 3 of the shaft is an annular chamber 6 enclosed by the cy-
35 lindrical sheet metal casing 7 and a base plate 8. This annular chamber 6 which also serves as a gas receiver, is extended downwardly so as partly to surround the fuel feed pipe 4 for the purpose of preheating and drying the fuel. Instead of the gas re-
40 ceiver 6 surrounding the upper portion of the fuel feed pipe 4, a separately heated chamber may be provided, which at its maximum temperature will produce partial dry distillation of the fuel in the pipe 4.
45 From the gas receiver 6 the gas is drawn through the pipe 9 into the main 10.

The fuel is fed to the producer by means of a rotary feed plunger 11 having a lower screw-threaded portion 11^a which fits into
50 an internally screw-threaded pedestal 12. The feed plunger 11 is provided with a driving gear 13 by means of which it can be rotated and simultaneously raised and lowered by the interaction of the screw-threaded portion 11^a with the internal screw-thread of the pedestal 12. The fuel is sup-

plied by means of a hopper 14 to a feed tray 15 having a base plate 16 in which the feed plunger is guided. The fuel is passed to the centre of the feed tray 15 above the piston 11 by means of a revolving annular member 17 supported on antifriction rollers and fitted with a number of scraper blades 19 fixed to scraper arms 18.

In the operation of the improved gas pro-
65 ducer, the feed plunger 11 moves continu-
ously up and down, and receives from the base plate 16 of the tray 15 a determined quantity of fuel which it forces into the mouthpiece 5 and thence to the shaft 1.

In order to prevent the fuel that has al-
ready been fed by the plunger from drop-
ping back, the cross-section of the mouth-
piece 5 is increased above its inlet end in
15 such a manner that an annular surface 20
is formed which provides a supporting
ledge for the fuel.

It is necessary for the piston 11 to rotate
in order to help it detach itself from the
fuel. The top 21 of the piston 11 is pref-
erably convex in order that the bottom sur-
face of the fuel in the mouthpiece 5 will be
concave. In the case of dry fuel, such
fuel is preferably moistened with a liquid
such as water, oil, tar, and the like, at its
surface of contact with the piston.

The lower part of the generator has a
very much smaller diameter than the upper
part, and therefore, in order that the fuel
shall not be pressed up into the shaft in the
form of a core of smaller cross sectional
area which, on arriving at the top, would
break up and roll about inside the shaft dis-
tributing means are provided in the shaft,
consisting of a pointed solid core 22 from
55 which partitions 23 extend radially out-
wards. Between these radial partitions 23
are arranged concentric partitions 24 held in
place by means of tongue-and-groove joints.
The partitions 24 may be set at any desired
angle to the vertical for the purpose of de-
flecting the ascending fuel more towards the
centre or more towards the outside as re-
quired.

The radial partitions 23 are hollow and
105 constitute gas outlets which communicate
with the outlet openings 31 in the lower part
3 of the producer. By this means an exceed-
ingly uniform withdrawal of the gas is pro-
vided for over the entire cross section of
110 the shaft.

The air for the generation of gas is sup-

plied to the gas producer from above through the layer of ashes. The removal of the ashes and slag is effected by hand or mechanically from the top of the burning fuel.

What I claim is—

1. A gas producer of the downward combustion type having the ash zone at the top of the producer shaft comprising in combination a producer shaft the cross-sectional area of which increases towards the top and is open at the top to admit the air for the generation of gas and allow the discharge of the ash, means for feeding the fuel from the bottom towards the top of the shaft, means for withdrawing the gas from below the ash zone without passing through the ash zone, whereby the combustion is caused to take place at the top of the shaft, the ash zone to remain at the top of the shaft, and the air to be supplied to the fuel through the ash zone.

2. A gas producer of the downward combustion type having the ash zone at the top of the producer shaft comprising in combination a producer shaft the cross-sectional area of which increases towards the top and is open at the top to admit the air for the generation of gas and allow the discharge of the ash, means for feeding the fuel from the bottom towards the top of the shaft, means comprising apertures in the narrow part of the producer shaft below the ash zone for

withdrawing the gas without passing through the ash zone, whereby the combustion is caused to take place at the top of the shaft, the ash zone to remain at the top of the shaft, and the air to be supplied to the fuel through the ash zone.

3. A gas producer of the downward combustion type having the ash zone at the top of the producer shaft comprising in combination a producer shaft the cross-sectional area of which increases towards the top and is open at the top to admit the air for the generation of gas and allow the discharge of the ash, a fuel-feed tube delivering into the lower part of the producer shaft, and a feed-plunger capable of rotating and moving vertically into the lower end of said fuel-feed tube for feeding the fuel from the bottom towards the top of the shaft, means comprising apertures in the narrow part of the producer shaft below the ash zone for withdrawing the gas without passing through the ash zone, whereby the combustion is caused to take place at the top of the shaft, the ash zone to remain at the top of the shaft, and the air to be supplied to the fuel through the ash zone, as set forth.

In testimony whereof I have signed my name to this specification.

HERMANN GOEHTZ.
